BUCKLE

Thomas A. Matthews and Moses A. Hicks, Richmond, Va., assignors to B. T. Crump Company, Inc., Richmond, Va., a corporation of Virginia

Filed Sept. 12, 1962, Ser. No. 223,049

1 Claim. (Cl. 24—196)

The present invention relates to a buckle and more particularly to a buckle for use with an adjustable web belt.

In the training of horses for harness racing, a training device is employed to teach the horse proper footwork. The training device comprises two leather or plastic loops interconnected by a web belt and a buckle to enable the spacing of the loops to be fitted to individual horses. The training procedure consists of fitting one of the loops around a front leg of the horse and the other loop around the corresponding rear leg of the horse. Since the loops are connected together, the training device will make the horse work his front leg and corresponding rear leg in unison.

In training devices of this nature, some difficulty has been experienced because the web belt is bent out of line as it passes through the buckle, hence, the forces transmitted through the buckle, between attached portions of the web belt, have followed a tortuous path. As a consequence of this difficulty, it is believed that training programs using this device have not progressed as quickly or as satisfactorily as they should. The present invention was conceived to obviate this difficulty.

It is an object of the present invention to provide a buckle for use with an adjustable web belt so that the belt may be readily released from the buckle in order to adjust the length of the web belt.

It is another object of the present invention to provide a buckle in which one end of the web belt is permanently fastened to the buckle while the other end of the web belt is detachably connected to the buckle so that it may be readily released therefrom or so that it may be loosened sufficiently while still remaining attached to the buckle for changing the length of the web belt by adjusting it.

It is another object of the present invention to provide a buckle having slidable means thereon which rigidly secure one end of a detachable web of the belt to the buckle at one time while permitting the detachable web portion of the belt to be sufficiently loosened in order to have the length of the belt adjusted to another size or length, and thereafter again rigidly secured to the buckle.

It is another object of the present invention to provide a buckle for attachment to an adjustable web belt in which force transmitted through the buckle and the belt passes through in a common plane.

It is another object of the present invention to provide a buckle for use with an adjustable belt having a sliding wedge member that co-acts with another member of the buckle so that the adjustable web belt portion is wedged between these two members and the wedging force is transmitted in the same plane in which the attached belt portions lie.

It is another object of the present invention to provide a buckle having a sliding member for binding the detachable end of a web belt and in which the opposite ends of the web belt and buckle are disposed in alignment with one another at all times, including the time when the detachable end of the belt is rigidly bound or fastened to the buckle.

It is another object of the present invention to provide a buckle for use with an adjustable web belt provided with a slidable member for rigidly securing the adjustable portion of the web belt to the buckle in which the

2

sliding member is provided with a planar surface that is coplanar with a stationary member of the buckle between which coplanar surfaces the adjustable portion of the web belt is wedged and in which the wedging force lies in the same plane as the main belt axis.

Various other objects and advantages of the present invention will be readily apparent from the following detailed description when considered in connection with the accompanying drawing forming a part thereof and in which:

FIGURE 1 is a plan view of the buckle embodied in the present invention; and

FIG. 2 is a section taken along the lines 2—2 of FIGURE 1.

15 Referring to the drawing, the reference numeral 10 generally designates a buckle provided with two parallel slide rods 11 spaced from each other by spacing end rods 12, at right angles thereto. The slide rods 11 have their opposite ends disposed in the end rods 12 in holes 13 provided in opposite ends of the rods 12 and are fixed thereto by pins 14.

The spacing end rods 12 in cross section, as best seen in FIGURE 2, have parallel flat side faces 15 and a flat or planar innerface 16 with an arcuate or curved outerface 17.

20 Slidably mounted on parallel slide rods 11, between spacing end rods 12, are rods 18 and 19. The rods 18 and 19 are provided with holes 20 and 21, respectively, near their ends, through which pass the parallel slide 30 rods 11.

The spacing end rods 12 are also provided with longitudinal, axial, rectangular slots or holes 24 through which the opposing ends of a web belt 27 are passed. The stationary end of the belt is on the left hand side as seen 35 in the drawing and is formed by passing the end 23 of the belt through the slot 24 of the left end rod 12, thence around the circumference of slidable rod 18 and then back through the same slot 24 so that it is doubled back upon itself to overlap the portion 22 and is sewn as indicated by 25 to fix permanently the stationary portion of the web belt to the buckle.

The other member 12 is provided with an identical slot 24 extending completely therethrough. The slots 24 are 45 substantially rectangular in cross section and are slightly wider than the width of the web belt. The slots 24 are also disposed in alignment with a plane passing through the axes of slide rods 11 and rods 18 and 19 so that all of these members are coplanar. The slots 24, of course, are disposed between the holes 13 of the spacing rods 12.

50 Spring biasing members 30 are mounted on each rod 11 between the slidable rods 18 and 19 to urge normally the rods 18 and 19 in a direction toward the adjacent spacing rod 12.

The slidable rod 19 is further provided with knurling 55 as indicated at 31 adjacent the major portion of its periphery. The outerface 32 of the rod 19 which is disposed opposite the innerface 16 of the adjacent rod 12 is flat and parallel with face 16 of the spacing rod 12 to provide a co-acting wedging action with the respective face 16 of rod 12, as hereinafter described.

The free end portion 34 of the web belt has its outer extremity or end 35 threaded through the slot 24 in the respective adjacent rod 12 and thereafter wrapped around the knurled circumference of the slidable rod 19 after which the end 35 is then threaded back through the slot 24 to overlap the portion 34 of the adjustable web portion of the belt, as best seen in FIGURE 2.

The slidable rod 19, by virtue of the spring 30 normally urging it in a direction toward its respective adjacent spacing end rod 12, causes the face 32 to wedge against the adjacent portions of the adjustable web portion of the belt and to wedge these portions against the inner-

face 16 of the respective adjacent rod 12. Hence, the belt is bound therebetween and the web belt is rigidly secured to the buckle.

The slideable rod 19 may be pushed back on the members 11 and away from its respective adjacent member 12 by applying a force thereto greater than the force in spring 30 in order to permit the adjustable portion 34 of the belt to be lengthened or shortened to the desired length. It is lengthened by decreasing the amount of overlap between 34 and 35, and shortened by increasing the overlap.

Since the slots 24 are in alignment with the entire assembly or frame of the buckle, and the sliding rod 19 and both the wedging face 32 and the respective co-acting face 16 of adjacent rod 12 are planar and parallel to each other and within the confines of the buckle frame, the forces transmitted between web portions 22 and 34 of the belt and through the buckle are transmitted in a common plane. Also, the operation of the faces 16 and 32, to bind the belt therebetween to connect fixedly the adjustable portion of the web belt, does not impart any knife edge or biting action to the belt so that it will not break or develop a weak point here.

Although the invention has been shown in terms of a preferred embodiment, nevertheless, changes and modifications will occur to those skilled in the art, which changes do not depart in principal from the inventive concepts herein taught. Such changes and modifications are deemed to come within the purview of the spirit and scope of the invention.

What is claimed is:

A belt buckle comprising two horizontal rod members, two vertical slotted end members having their opposite ends fixedly connected to the opposite ends of said rod members, a vertical cylindrical member fixedly carried on said rod members, said cylindrical member being spaced adjacent one of said end members for wrapping a portion of a web belt threaded through said adjacent end member therearound, a vertical slideable member having spaced apertures therein slidably disposed on said rod members adjacent another of said end members, a spring member disposed on each of said rod members between said cylindrical and slideable member for urging said slideable member toward its respective adjacent end member, the longitudinal axis of said rod members and end members cylindrical and slideable members and the slots in said end members being coplanar, said slideable member having an arcuate knurled periphery with a planar face on one side thereof, said respective adjacent end member having a planar face opposite the planar face of said slideable member, said faces being parallel, whereby an adjustable belt portion passing between said faces is detachably wedged between said faces.
